NEWSPAPER DISPENSING APPARATUS

Lou's Hatcher, Washington, D. C., and
Creel W. Hatcher, Valley Forge, Pa.

Application February 27, 1945, Serial No. 579,996

7 Claims. (Cl. 312—57)

1

This invention relates to apparatus designed primarily for dispensing newspapers although it is to be understood that it can be used for dispensing other items such as magazines, pamphlets, and the like.

It is an object of the invention to provide an apparatus which can be check controlled and which, when actuated, will operate to remove one newspaper or the like from a magazine and deliver the same to the customer.

Another object is to provide new means by which the engaged article can be dispensed without regard to its thickness and which will automatically reset itself after each delivery operation.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a vertical longitudinal section through the apparatus, the same being shown provided with a supply of newspapers or the like to be dispensed.

Figure 2 is an enlarged side elevation of the dispensing mechanism and illustrating various positions assumed by the article engaging portion of the apparatus during the operation of picking up and delivering an article.

Figure 3 is a view partly in elevation and partly in transverse section showing a portion of the magazine and adjacent parts, portions being broken away.

Referring to the figures by characters of reference 1 designates a casing formed of any desired material and provided with a partition 2 which can include longitudinal and end supporting strips 3 on which are mounted floor plates 4 spaced apart at their inner edges to provide a slot 5 extending longitudinally of the partition. The casing 1 and partition 2 cooperate to form a magazine or chamber for holding newspapers A or the like to be dispensed. A guide rod 6 is located beneath the slot 5 and is fixedly connected at its ends to the frame formed by the strips 3 and slidably mounted on this rod is a sleeve 7 having a lug 8 extended upwardly therefrom through the slot 5. A follower

2

9 is hingedly connected to the lug and is normally supported in an upwardly and rearwardly inclined position by a stop arm 10 extended from the sleeve 7 and through the slot 5 as shown particularly in Fig. 1. A coiled spring 11 is mounted on rod 6 and asserts a constant thrust against sleeve 7 so that, in the absence of any blocking means, said sleeve and the follower connected thereto will be positioned at the front or delivery end of the partition.

The partition 2 terminates backwardly from the inclined front wall 12 of the casing and this front wall constitutes the front of a chute 13 which extends throughout the width of the partition and downwardly from said partition to a trough 14 at the lower end of the chute. This chute constitutes the outlet for merchandise dispensed by the machine.

A stop flange 15 is extended above the partition 20 for a short distance and is preferably in line with the back wall 16 of chute 13. Extended into the chute from the lower portion of this flange and below the level of the top of the stop flange 15 are upwardly and forwardly curved fingers 17 which can be widely spaced. Any desired number of these fingers can be used and they cooperate with the top flange to form a supplemental catching device as hereinafter explained. The front wall 12 of the chute is provided on its 30 back surface and above the level of flange 15 and fingers 17 with a stripping plate 18 which can be angular in cross section and extends throughout the width of the interior of the chute, this plate overhanging a portion of the chute as shown.

A shaft 19 is journaled within the casing 1 and is adapted to be driven by worm gearing 20 receiving motion from an electric motor M or other suitable source of power. This motor can be started and stopped by any suitable mechanism which can be check controlled if desired. A crank arm 21 is connected to each end portion of shaft 19 so as to rotate therewith and it is intended that, during the operation of the apparatus, one article will be dispensed during each complete rotation of shaft 19. This shaft is normally positioned with the crank arms 21 extended forwardly in substantially horizontal positions and both of the crank arms are pivotally connected at 22 to the lower ends of the sides of a dispensing means including a frame 23. The top of this frame is formed of a connecting bar 24 which is held detachably to the sides of the frame in any suitable manner, as 55 by means of spring clips or tongues 25. The

bar can be provided with flattened ends 26 (see Figure 2) which are in detachable engagement with the sides of the frame but fit snugly in said sides so as to be held normally against rotation relative to the sides.

Extending in one direction from the bar 24 are sharp needles 27 which project a length less than the thickness of the article to be dispensed. Two or more of these needles can be extended in one direction from the bar and in practice these needles are located where they can penetrate backwardly into the article to be dispensed, when the frame 23 is operated in the manner herein-after described. More than two sets of needles can be used. For example, a second set of needles 28 can be extended from the bar in a direction opposite to the needles 27 and one set of needles can be longer than the other so as to adapt the apparatus for use in dispensing articles widely differing in thickness by adjusting bar 24.

At a point between the ends of each side bar of frame 23 there is provided a fulcrum element including a yoke 29 pivotally supported at the center by a pin 30 mounted in a depending bracket 30' secured to frame 3. A rod 31 is mounted for reciprocation within each yoke and has a guide block 32 fixedly positioned on an intermediate portion thereof. The side bar of frame 23 nearest each yoke is slidably longitudinally in the block 32 carried by the yoke and springs 33 are mounted on rod 31 between block 32 and the ends of yoke 29 so as to urge the block 32 normally toward the center of the yoke. Thus the frame is free also to slide transversely with the rods 31, such movement being restrained by the springs. It is to be understood that the parts are so located and proportioned that when a horizontal stack of newspapers or the like, indicated at "A," is positioned between flange 15 and the follower 9, the spring 11 will be held under compression and obviously the degree of compression will increase in proportion to the length of the stack. It is to be understood that the newspapers or the like when placed on the partition plates 4 and back of the flange 15 will have their folds lowermost. When at the point of starting, the dispensing mechanism is positioned with its bar 24 located at point "a" in Fig. 2. When the newspaper is to be dispensed the gearing 26 is set in motion by check controlled means such as motor M or the like and will cause the cranks 21 to make one complete rotation from the point X in the direction indicated by the arrow in Fig. 2. During the first part of this rotation the lower end of the frame 23 will swing toward the right in Figure 2 along a short arcuate path past the axis of the shaft 19. Since the frame 23, intermediate its upper and lower ends, passes through the blocks 32 of the fulcrum elements, the short swinging movement of the lower end of the frame will produce a swinging movement of the bar 24 at the upper end, but in the opposite direction. In other words the bar 24 will move from position a across the chute to position b and cause the needles to drive into the first newspaper in the magazine. The bar will then move in an upward direction until it reaches position c. During this time the forward springs 33 have been placed under compression because of the pressure exerted thereagainst by the side bars of frame 23 under the action of the crank arms 21. The engaged newspaper will be slid upwardly by the needles until the bottom or fold portion has risen well above the flange 15. As bar 24 reaches position c the cranks 21 move

toward the vertical center of shaft 19 with the result that the front springs 33 which previously had been placed under compression will expand as thrust blocks 32 are moved to positions substantially at the centers of the yokes 29 where the two springs 33 are equalized. While the blocks are thus located the crank arms 21 will continue their counter-clockwise movement and when said cranks move to the left in Figure 2 over the axis of rotation of shaft 19, the bar 24 will travel in an arcuate path in a direction opposite to the path traveled by the cranks and move from position c to position d. This movement will continue as the crank arms travel toward the left in Fig. 2. During such movement the pins on which the first newspaper or the like is impaled will carry the same forwardly within the chute 13 until the bar comes into contact with the stripping plate 18. Further counter-clockwise movement of crank arms 21 will pull the frame 23 downwardly from position d to position e and this operation will result in placing the rear springs 33 under compression. As continued counter-clockwise movement of the crank arms takes place, bar 24 will be pulled to a position below the stripping plate 18 whereupon the compressed rear springs 33 will snap bar 24 forwardly from position e to position a, which was the point of starting. As the impaled newspaper or the like cannot follow the bar because of the position of the stripping plate 18, the needles on the bar will be withdrawn from engagement with the newspaper A or the like and said paper permitted to gravitate through the frame and downwardly within the chute 13.

It has been determined through experiment that if any part of a folded newspaper is engaged and pushed upwardly when its fold is lowermost, and the newspaper is in position against other newspapers in a horizontal stack, all parts of the engaged newspaper will move as one body. Therefore it is not necessary for the needles to penetrate the entire thickness of the engaged newspaper in order to insure proper delivery. Consequently newspapers of different thicknesses can be delivered without requiring adjustment. However, in order to insure against any failure should newspapers of considerable thickness be placed in the magazine, one or more sets of needles of greater length could be brought into position to engage the newspapers if so desired. It is for this reason that a second set of needles has been indicated at 28.

If by any chance the newspaper to be dispensed should drag a second newspaper out of proper position back of flange 15, said second newspaper would be disposed back of the fingers 17 when relieved from pressure by the movement of the first newspaper from position c to position d. Thus it would be retained where it could be engaged and delivered during the next operation of the apparatus.

In Fig. 2 the crank arms 21 have not been shown in their normal positions but are in an intermediate position. The point of starting of the cranks when bar 24 is at position a has been indicated generally at "X" and during the one complete rotation of the crank arms they will start at this point "X" and stop when they arrive at the same point.

What is claimed is:

1. In a dispensing apparatus the combination with a delivery chute, a magazine opening thereinto and a stop at the chute end of the magazine,

of means for pressing a stack of articles toward the stop to hold one of the articles against the stop, a bar extending transversely of the magazine, means on the bar for penetrating the article to be dispensed at a point in said article between the edges of the article, and means for moving the bar in an endless path to successively drive said penetrating means into the article to be dispensed, shift the bar to disengage the penetrated article from the stop, move the bar from the magazine and into the chute to convey the engaged article into the chute, and return the bar to its point of starting, said means including a spring positioned to exert yielding pressure through the bar and the penetrating means against the article to be dispensed while said article is being disengaged from the stop.

2. In a dispensing apparatus the combination with a delivery chute, a magazine opening thereto and a stop at the chute end of the magazine, of means for pressing a stack of articles toward the stop to hold one of the articles against the stop, a bar extending transversely of the magazine, means on the bar for penetrating the article to be dispensed at a point in said article between the edges of the article, means for moving the bar in an endless path to successively drive said penetrating means into the article to be dispensed, shift the bar to disengage the penetrated article from the stop, move the bar from the magazine and into the chute to convey the engaged article into the chute, and return the bar to its point of starting, said means including a spring positioned to exert yielding pressure through the bar and the penetrating means against the article to be dispensed while said article is being disengaged from the stop, and a stripping device positioned in the chute in the path of the engaged article.

3. In a dispensing machine the combination with a delivery chute, of a magazine opening thereto for holding a series of articles to be dispensed, a stop at the chute end of the magazine, means for pressing said articles toward the stop, a fulcrum element pivotally mounted, a frame movable longitudinally and transversely on and relative to said fulcrum element and including a bar extended transversely of the articles to be dispensed, a needle extending from the bar, means for simultaneously rocking the frame and fulcrum element and reciprocating the frame longitudinally and transversely relative to the fulcrum element thereby to move the bar in an endless path within the chute to successively drive the needle into one of said articles at a point between the edges of the article, disengage that article from the stop, and move the engaged article from the magazine and into the chute for gravitation within the chute, and yielding means for restraining said transverse movement of the frame.

4. In a dispensing apparatus the combination with a delivery chute, of a magazine opening thereto, a stop at the chute end of the magazine, a supplemental catching device extending into the chute below the level of the top of the stop and spaced from and diverging upwardly from said stop, yielding means for pressing the articles to be dispensed in the direction of the stop, a frame, means for reciprocating and rocking the frame, said frame including a cross bar positioned for reciprocation and oscillation in the chute, and means carried by the bar for successively penetrating one of the articles to be dis-

pensed, lifting said article above the stop, and conveying the article into the chute.

5. In a dispensing apparatus a magazine having an outlet end, a stop at said end, yielding means for automatically pressing toward the stop the articles to be dispensed, a frame mounted for up and down and back and forth reciprocation and simultaneous rocking, said frame including a bar extended transversely of the articles to be dispensed, means on the bar for penetrating the article to be dispensed, means for actuating the frame to move the bar in an endless path and in a direction to successively drive the penetrating means into one of said articles at a point between the edges of the article, shift the penetrated article away from the stop, and convey the article through the outlet end of the magazine, and yielding means for restraining the back and forth reciprocation of the frame.
- 10 20 30 40 50 60 70 80 90 100 110 120 130 140 150 160 170 180 190 200 210 220 230 240 250 260 270 280 290 300 310 320 330 340 350 360 370 380 390 400 410 420 430 440 450 460 470 480 490 500 510 520 530 540 550 560 570 580 590 600 610 620 630 640 650 660 670 680 690 700 710 720 730 740 750 760 770 780 790 800 810 820 830 840 850 860 870 880 890 900 910 920 930 940 950 960 970
6. In a dispensing apparatus a magazine having an outlet end, a stop at said end, yielding means for automatically pressing toward the stop the articles to be dispensed, a frame mounted for up and down and back and forth reciprocation and simultaneous rocking, said frame including a bar extended transversely of the articles to be dispensed, means on the bar for penetrating the article to be dispensed, and means for actuating the frame to move the bar in an endless path and in a direction to successively drive the penetrating means into one of said articles at a point between its edges, shift the penetrated article away from the stop, and convey the article through the outlet end of the magazine, normally tensioned opposed springs for restraining the back and forth reciprocation of the frame, and means supported in the path of the article being conveyed for stripping said article from the penetrating means while outside of the magazine and successively placing one of the springs under compression and then releasing the same, thereby to accelerate return of the penetrating means to article engaging position.
7. In a dispensing apparatus a magazine having an outlet end, a stop at said end, yielding means for automatically pressing toward the stop the articles to be dispensed, a frame mounted for simultaneous reciprocation and oscillation, said frame including a bar extended transversely of the articles to be dispensed, means on the bar for penetrating the article to be dispensed, and means for actuating the frame to move the bar in an endless path and in a direction to successively drive the penetrating means into the article to be dispensed, shift the penetrated article away from the stop, and convey the article through the outlet end of the magazine, said frame operating means including a rotatable crank engaging the frame, a yoke mounted for rocking movement, a guide block centered in the yoke and slidably engaged by the frame, and opposed springs in the yoke for holding the block normally centered in the yoke.
